UNITED STATES PATENT OFFICE

MAX BICHEROUX, OF AACHEN, GERMANY, ASSIGNOR, BY MESNE ASSIGNMENTS, TO THE AMERICAN BICHEROUX COMPANY, A CORPORATION OF DELAWARE

PROCESS AND APPARATUS FOR THE MANUFACTURE AND LEERING OF GLASS SHEETS

Application filed August 6, 1928, Serial No. 297,666, and in Germany April 7, 1928.

In the leering of glass sheets formed by the so-called intermittent forming process, such for instance as the Bicheroux process, certain difficulties arise from the fact that the speed at which the sheet is formed is much higher than the speed at which it is desirable to feed the sheet through the leering.

If the sheets as formed are received on a take-off member which carries them away from the forming pass at the speed of sheet formation and are delivered from the member to the leering conveyor, there is in all systems known today a change of speed of the travel in the sheet of glass, and this is generally accomplished by intricate mechanisms to cause a variation in the speed of a part of the sheet carrying device.

My present invention provides a system in which the sheets may be formed at high speed and properly deposited on a take-off and fed through a leering at low speed without having its speed of travel altered. This I accomplish by depositing the sheet on a conveying member which moves the sheet at the speed at which the sheet is to be fed in leering and from which it is fed into the leering, and moving the point of sheet formation in a direction opposite to that in which the sheet is moved by the conveyor at a speed equal to or if preferred, slightly greater, than the difference between the speed of travel during leering and the speed of sheet formation. To accomplish this my invention consists in the method hereinafter described and in mechanism for carrying out the same.

In this application I have shown one form of such mechanism but it will be understood that this may take different forms.

Referring to the accompanying drawing in which corresponding parts are designated by corresponding marks of reference,—

Figure 1 is a diagrammatic side elevation of a mechanism invented by me and adopted to carry out the improved method.

Figure 2 is a vertical transverse section on line $x-2-x2$ of Figure 1.

In this drawing, A represents a part of a leering of any improved construction provided with proper means for moving a sheet of glass therethrough. In the drawing these

means are shown as a series of rolls B which form a feeding bed for the sheets fed therethrough. Before the entrance of the leering, is located the take-off table C which receives the glass sheet from the forming mechanism and delivers it into the leering. This table has a sheet feeding surface which in the form shown is composed of a series of rollers D driven by a longitudinal shaft E from the drive of the leering conveyor, and is in the form shown, a forward continuation of the latter, so that the peripheral speed of the rolls D is the same as that of the initial rolls B of the leering conveyor.

Located above the take-off table C is the forming pass F, made by the gap between the sheet forming rolls G and G'. These rolls are mounted on a frame H straddling the table C and movable lengthwise of the table on tracks $h-h$, by any suitable means such as a motor h' connected to and driving the wheels h^2 . As the forming mechanism shown is of the Bicheroux type, a glass receiver h^3 is shown adjacent to the forming pass. On this receiver is accumulated the molten glass from which the sheet is formed.

While I have shown a forming device of this type, any other forming devices could be used in carrying out my invention.

With the parts so arranged and the rolls B and D revolving, glass is poured on the receiver h^3 with the frame H at a point intermediate the length of the table C, the forming rolls are rotated and the frame H put into motion away from the leering with a speed of translation substantially equal to the difference between the speed at which the sheet is issued from the forming machine and the peripheral speed of the slowly revolving rolls D. Thus the point of origin or formation of the sheet is shifted during the formation of the sheet in a direction opposite to the direction of the feeding of the sheet. The sheet is fed by the rotation of the rolls D to the leering. It will of course be understood that after the delivery of the entire sheet to the table C the sheet may, if desired, be given any desired motions thereon without losing that desirable feature of my invention which permits a sheet formed at high speed to be

delivered to a take-off bed without necessitating a high speed of translation of the sheet on that bed.

Having thus described my invention what I claim and desire to secure by Letters Patent is:—

1. The hereinbefore described method of forming and leering glass sheets which comprises moving a sheet as formed towards the 10 leer, moving the point of sheet formation away from the leer during the formation of the sheet, and moving the formed sheet through the leer at a speed less than that of sheet formation.

15 2. Apparatus for making a sheet of glass, comprising a leer having continuously operating forwarding means, a runway at the entrance end of the leer also having continuously operating forwarding means constituting an extension of the forwarding means in the leer, a car mounted for movement back and forth along the runway, means for moving the car, a pair of sizing rolls carried by the car above the runway, and means for rotating the sizing rolls as the car is moved back along the runway at a rate of peripheral speed which is greater than the speed of movement of said forwarding means and which is also greater than the rate of movement of the car.

3. Apparatus for making a sheet of glass, comprising a roller leer having a roller runway at its entrance end constituting a continuation of the leer runway, a car mounted 35 for movement along the runway, a pair of sizing rolls carried by the car above the runway, and driving means for the car, the sizing rolls and the leer and runway rolls arranged to give the sizing rolls a rate of peripheral speed which is greater than the peripheral speed of the leer and runway rolls and also greater than the rate of movement of the car.

4. The combination with a sheet glass forming machine, of a leer, means for receiving a sheet from the forming machine and feeding it through the leer at leering speed, and means for moving the forming machine away from the leer during the formation 50 of the sheet at a speed equal to the difference between the speed of sheet formation and the speed of feed through the leer.

5. An apparatus for making a sheet of glass, comprising a leer having a continuously operating forwarding means, a runway at the entrance of the leer also having continuously operating forwarding means constituting an extension of the forwarding means in the leer, a car moving back and forth above the runway, a pair of sizing rolls rotating in the car, said sizing rolls being driven at a rate of peripheral speed which is greater than the speed of movement of said forwarding means and which is also greater than the rate of movement of the

car by an amount which is approximately equal to the rate of movement of said forwarding means.

6. Apparatus for making a sheet of glass comprising a roller leer having a roller runway at its entrance and constituting an extension of the leer runway, a car moving along the runway, a pair of sizing rolls carried by the car, driven at a peripheral speed greater than the peripheral speed of the leer 75 and runway rolls, and also greater than the rate of movement of the car by an amount which is approximately equal to the peripheral speed of the leer and runway rolls.

7. Apparatus for making a sheet of glass 80 comprising a leer having continuously operating forwarding means, a runway at the entrance end of the leer also having continuously operating forwarding means constituting an extension of the forwarding means in the leer, a car mounted for movement back and forth along the runway, a pair of rotatable sizing rolls carried by the car, rotated as the car is moved back along the runway 90 at a rate of peripheral speed which is greater than the speed of movement of said forwarding means and which is at least equal to the rate of movement of the car.

8. Apparatus for making a sheet of glass, comprising a leer having continuously operating forwarding means, a runway at the entrance end of the leer also having continuously operating forwarding means constituting an extension of the forwarding means in the leer, a car mounted for movement back and forth along the runway, means for moving the car, a pair of sizing rolls carried by the car above the runway, and means for rotating the sizing rolls as the car is moved back along the runway at a rate of peripheral speed which is greater than the speed of movement of said forwarding means and which is also greater than the rate of movement of the car by an amount which is approximately equal to the rate of movement 110 of said forwarding means.

9. Apparatus for making a sheet of glass, comprising a roller leer having a roller runway at its entrance end constituting a continuation of the leer runway, a car mounted 115 for movement along the runway, a pair of sizing rolls carried by the car above the runway, and driving means for the car, the sizing rolls and the leer and runway rolls arranged to give the sizing rolls a rate of peripheral speed which is greater than the peripheral speed of the leer and runway rolls, and also greater than the rate of movement of the car by an amount which is approximately equal to the peripheral speed of the 120 leer and runway rolls.

In testimony whereof I hereunto affix my signature.

MAX BICHEROUX.
